UNITED STATES PATENT OFFICE.

FRED L. PEACH, OF DALTON, MASSACHUSETTS.

FLOWER-STAND.

SPECIFICATION forming part of Letters Patent No. 678,081, dated July 9, 1901.

Application filed March 29, 1901. Serial No. 53,453. (No model.)

To all whom it may concern:

Be it known that I, FRED L. PEACH, a citizen of the United States of America, residing at Dalton, in the county of Berkshire and State of Massachusetts, have invented new and useful Improvements in Flower-Stands, of which the following is a specification.

This invention relates to flower-stands having a swinging movement at one side of a window or similar opening, whereby flowers carried thereon are swung to positions directly before and into the full light therefrom or to one side of a window or to any convenient position intermediate of the above-mentioned ones; and the invention consists in the peculiar construction of said stand, whereby it is adapted to provide safe and suitable supports for a number of pots of flowers and is adapted to have the requisite swinging movements.

In the drawings forming part of this specification, Figure 1 is a side elevation of a flower-stand constructed according to my invention, this figure showing a window and window-frame behind the flower-stand. Fig. 2 is a sectional view on line 2 2, Fig. 1.

Referring to the drawings, 2 indicates the main post of the flower-stand, which is preferably square in cross-section or has two opposite flat sides for a purpose below described and of suitable length to extend from near the floor of a room to the upper part of a window-frame 12, and said post is pivotally supported in said position as follows: Each end of said post is capped by a metallic ferrule 15, through which project two pivot-pins, (one of which is shown at the top of Fig. 1.) The lower end of said post is supported for rotary movement on a raised standard, of metal, preferably, and the upper end is supported in a bracket 4, projecting from the upper end of said window-frame 12. A post 5 constitutes the border of the flower-stand opposite to said main post 2 and is also preferably of rectangular form in cross-section, as shown in Fig. 2, and the said

two posts are united to form a frame of sufficient rigidity and strength to support safely a number of flower-pots filled with earth, as shown. Between said posts 2 and 5 extend horizontally a series of shelf-supporting bars 8, which are connected by both ends thereof to said posts by the brackets 16, preferably of metal, which are suitably secured to the

bars and posts in the positions shown, thereby largely contributing to the rigid resistance of the frame against any downward or sagging movement of the outer section of the main frame part of the stand. Further means in addition to said brackets 16 for stiffening said frame are provided by the brace 6, between the lower part of said post 2 and the lower end 55 of said post 5, and by the inclined tie-rod 7, between the upper end of said posts 2 and 5, said rod passing through the post 5 and bringing a head thereon to bear against the latter-named post and passing through said post 2, 60 having a nut on the end thereof screwing against the side of the latter, as shown, a wedge-shaped washer 17 being inserted between said nut and the side of the post. The extremities of said post 5 are preferably 65 capped with cylindrical ornaments, as shown.

The shelves 9 of the stand are preferably of wood, and one end thereof is slotted, as shown in Fig. 2, and they are thus adapted to be retained upon bars 8 for holding the flower-pots 75 by the position of the post 2 at the base of said slot, as shown in Fig. 2 most clearly, and by the abutment of the outer or opposite end of the shelf against the inner side of the post 5. Thus each shaft lies flat on the upper 80 side of one of said bars 8, and owing to the abutment of the opposite walls of said slot against the sides of the post 2 the shelf is held against any movement that would tend to throw the flower-pots off. Thus the shelves 85 are made removable for cleaning, if desired, and no fastenings are required for holding them in operative positions on the stand.

The stand is conveniently swung before the window, as shown, for exposing the flowers to the light or may be swung entirely away therefrom to one side, and it is so arranged that the curtain 14 may be conveniently adjusted, whether the stand be before the window or not.

Having thus described my invention, what I claim, and desire to secure by Letters Patent of the United States, is—

1. A flower-stand having a frame comprising a main post having two opposite flat sides, 90 and an outer border-post, several shelf-supporting bars extending between said two posts and secured by their ends to the latter, a brace extending between the lower ends of

said posts, and a tie-rod extending between the upper ends thereof, a series of shelves laid on said bars in one end of each of which shelves is a longitudinal slot which incloses 5 said main post, thereby retaining the shelves in longitudinal positions on said bars, a stand pivotally supporting the lower end of said main post, and a bracket pivotally supporting the upper end thereof opposite a window-casing or like 10 place, substantially as described.

2. A flower-stand having a frame comprising a main post having two opposite flat sides, an outer border-post, several shelf-supporting bars extending between said two posts, 15 brackets under each end of said bars secured to the latter and to said posts, a brace extending between the lower ends of said posts, and a tie-rod extending between the upper ends thereof, a series of shelves laid on said 20 bars in one end of each of which shelves is a longitudinal slot which incloses said main post, the opposite ends of said shelves lying against the inner side of said outer post, thereby retaining said shelves in longitudinal 25 positions on said bars, a stand pivotally

supporting the lower end of said main post, and a bracket pivotally supporting the upper end thereof opposite a window-casing or like place, substantially as described.

3. A flower-stand having a frame comprising a main post having two opposite flat sides, an outer border-post, several shelf-supporting bars extending between said two posts, brackets under each end of said bars secured to the latter and to said posts, a brace extending between the lower ends of said posts, and a tie-rod extending between the upper ends thereof, a series of shelves supported on 30 said bars and there retained without other fastenings than the engagement of the extremities thereof with said main and outer border-posts, a stand pivotally supporting the lower end of said main post, and a bracket pivotally supporting the upper end thereof opposite a window-frame or like place, substantially as described.
